J. FORT.

UNDERBEAMER.

APPLICATION FILED JAN. 22, 1907. RENEWED APR. 22, 1908.

905,303.

Patented Dec. 1, 1908.

UNITED STATES PATENT OFFICE.

JAMES FORT, OF LOS ANGELES, CALIFORNIA, ASSIGNOR OF ONE-HALF TO GEORGE CARTLING,
OF LOS ANGELES, CALIFORNIA.

UNDERREAMER.

No. 905,303.

Specification of Letters Patent.

Patented Dec. 1, 1908.

Application filed January 22, 1907, Serial No. 353,461. Renswed April 22, 1908. Serial No. 428,695.

To all whom it may concern:

Be it known that I, JAMES FORT, a citizen of the United States, residing at Los Angeles, in the county of Los Angeles and State of California, have invented new and useful Improvements in Underreamers, of which the following is a specification.

My invention relates to that class of devices by means of which the walls of a well hole may be enlarged below the well-casing; and the object of my invention is to provide a simple, durable and effective device therefor, having but few parts, easily assembled and disassembled and which are not easily lost in the bottom of the well hole. I accomplish these objects by means of the device described herein and shown in the accompanying drawings in which:

Figure 1—is a longitudinal section partly in elevation and partly broken away, of my under reamer in its closed or inoperative position in-place in the casing of the well. Fig. 2—is a like view of my reamer in its spread out or operative position below the end of the casing. Fig. 3—is an elevation of the device removed from the casing showing the mandrel (top broken away) with the cutters secured thereto in their operative position. Fig. 4—is a transverse section taken on line 4—4 of Fig. 2. Fig. 5—is a perspective view of one of the cutters.

In the drawings 1 represents the well casing and 2 the mandrel to which is secured the cutters 3. These companion cutters, two in number, each one like the other are secured at their upper ends to the cutter retracting rod 4 by means of the pintle bolt 5 which passes through the holes 24 in the top of the cutters. The retracting rod is held in its elevated position by means of the coil spring 6, the function of which will be understood by means of the drawings. This coiled spring rests upon the annular ring 7 and this ring is held in place in the ring-secur ing bolt 8 which passes through the mandrel and the ring. The bore in this ring is sufficiently large to permit the free movement therein of the retracting rod, but this rod is held in place by means of the head 9 on the upper end thereof. This will provide one means (other means being also employed) to prevent the loss of the cutters in the well hole which occasions great loss and delay when it occurs owing to the difficulty of retrieving the device or parts thereof

when lost in the well hole. Extending transversely through each cutter is an inverted L-shaped slot 10 through which, when the cutters are in place in the mandrel, the cutter securing bolt 11 passes.

When the cutters are moved into the position shown in Fig. 2 below the lower end of the casing, the spiral spring will elevate the retracting rod 4 which will carry the cutters upwardly until the securing bolt passes into the lower leg of the inverted L-shaped slot 10 and this will cause the cutters to be thrown into their expanded or operative position. When the cutters are in their expanded or operative position as shown in Fig. 2 the shoulder 12 on the cutter will rest against the shoulder 13 of the mandrel and the shoulder 14 on the cutter will rest against the main body of the mandrel as at 15 (see Fig. 3). The shoulder 16 on the cutter will rest against and abut the mandrel as at 17. The shoulder 18 on the cutter will abut and rest against the shoulder 19 on the mandrel and the shoulder 20 will abut and rest against the shoulder 21 of the companion cutter. Lugs 2' on the lower end of the mandrel are adapted to project into recesses 3' in the cutters and secure the same against any lateral movement which may be induced by a side pressure against the lower ends of the cutter. As more particularly shown in Figs. 3 and 5 the cutters are interlocking, the lower ends being wider than the upper ends and overlapping each other. By this construction of the cutters a maximum of material is put into a minimum of space thus making the cutters as strong and durable as possible. Thus it will be seen that the shoulders on the cutters abutting the mandrel will be such as to give the cutters great strength and rigidity and abundant bearing abutment to cause the cutters to operate firmly and effectively. When power is applied to elevate the cutters out of the casing the shoulder 22 on the cutters will contact with the lower end of the well casing and the rod 11 will pass upwardly into the position shown in Fig. 1 causing the cutters to assume a closed or inoperative position as shown in Fig. 1, when the device can be easily withdrawn from the well hole—the configuration of the slot 10 in the cutters being such as to throw the cutters into their closed position when the cutter-holding rod 11 is forced into the upper end of the slot as it will when the mandrel is drawn out of the

casing. It will be next to impossible to lose the cutters or either of them or any part of the device in the well hole without breaking the cutter-securing rod 11 which passes through each of the cutters and into the mandrel on either side thereof and this rod can be made large enough to prevent its breaking.

Having described my invention what I claim is:—

10. 1. An under reamer comprising a mandrel, and interlocking cutters on the lower end of said mandrel, said cutters being provided with recesses therein and said mandrel being provided with lugs on its lower end adapted to fit into said recesses.
15. 2. In an under reamer, a mandrel, a plurality of interlocking cutters at the lower end of said mandrel, said cutters being provided with recesses therein and said mandrel being provided with lugs adapted to fit into said recesses and further provided with shoulders adapted to prevent the upward movement of

said cutters, and resilient means to hold said cutters in engagement with said shoulders.

3. In an under reamer, a hollow mandrel, a plurality of interlocking cutters at the lower end of said mandrel, said cutters being provided with recesses therein and said mandrel being provided with lugs adapted to enter said recesses and prevent the transverse movement thereof, and being further provided with shoulders adapted to prevent the upward movement of said cutters, and spring means secured to said cutters whereby said cutters are retained in position against said shoulders.

In witness that I claim the foregoing I have hereunto subscribed my name this 9th day of January, 1907.

JAMES FORT.
